UNITED STATES PATENT OFFICE.

CLEMENT F. STREET AND NATHAN M. LOWER, OF SCHENECTADY, NEW YORK, ASSIGNEES TO THE LOCOMOTIVE STOKER COMPANY, OF WILMERDING, PENNSYLVANIA, A CORPORATION OF PENNSYLVANIA.

FUEL-DISTRIBUTER.

1,195,530.

Specification of Letters Patent. Patented Aug. 22, 1916.

Application filed January 12, 1912. Serial No. 670,836.

To all whom it may concern:

Be it known that we, CLEMENT F. STREET and NATHAN M. LOWER, both citizens of the United States, residing at Schenectady, in 5 the county of Schenectady and State of New York, have invented certain new and useful Improvements in Fuel-Distributors, of which the following is a specification.

This invention relates to fuel distributors 10 for furnaces, and is particularly adapted for use in connection with mechanical stokers for locomotive boiler furnaces in which the lump fuel is fed in through the distributors by means of a jet or blast of steam or other 15 fluid under pressure as set forth in our prior application Ser. No. 652,462, filed October 2, 1911.

One of the objects of this present invention is to provide an improved form of distributor having a wide shield-like extension 20 at the top beyond the open end and having deflecting ribs or surfaces for distributing the fuel throughout the length of the firebox. This form is especially desired for 25 use at the sides of the furnace.

Another object is to prevent to a large extent, the warping of the distributors due 30 to the excessive heat to which they are subjected, and for this purpose longitudinal diverging ribs are provided on the top of the distributors.

In the accompanying drawings: Figure 1 is a plan of one form of our improved distributing device; Fig. 2, a longitudinal section of same; Fig. 3, a plan with a portion in horizontal section, showing a slight modification; Fig. 4, a longitudinal section of the same, a portion of the elbow being shown in elevation; Fig. 5, an inside end view; Fig. 40 6, an outside end view of the distributor shown in Figs. 3 and 4; and Fig. 7, an inside end view of the distributor shown in Figs. 1 and 2.

According to the construction shown in 45 the drawings, the improvement is illustrated as applied in connection with that type of distributor having a cylindrical body, 19, adapted to be inserted from within the furnace through the opening, 21, in the furnace 50 wall, or water leg of the fire box, and detachably connected to the elbow, 19^a, on the outside of the boiler, the elbow having connections for fuel supply, an air inlet opening,

27, and a fluid pressure blast, 28, all as set forth and claimed in our co-pending application, Ser. No. 670,835 filed of even date herewith.

When used as side distributors, as in the present instance, it is desired that the fuel should be evenly distributed through the length of the fire box and to the far corners, and for this purpose the inner end of the distributor may be formed at the top with a broad flaring hood or shield-like extension, 23, projecting beyond the fuel discharge opening, 22, and as shown, the under surface of the shield may be slightly curved at the sides to meet the short downwardly projecting flanges, 25, at the longitudinal edges of the shield. 70

The bottom of the distributor at the discharge opening is provided with a thickened portion in the form of a wedge-like deflector, 24, for diverting the fuel upward at this point against the under surface of the shield 23.

As shown in Figs. 3, 4, and 5, the lateral extension of the shield is principally at one side of the center line of the distributor, and in this case a deflecting rib, 26, is located on the under side of the shield for diverting a portion of the fuel toward the middle portion of the furnace grate. 80

For the purpose of preventing the warping of the broad extension shield or hood, 23, due to the high temperature to which it is exposed in the furnace, the longitudinally diverging ribs, 29, are provided on the top of the shield. 85

As the side distributors are usually designed to receive their fuel supply through inclined pipes, the elbow portion, 19^a, is preferably turned at an angle to the vertical, as shown more particularly in Fig. 6. 90

As the fuel is driven through the distributor by the steam blast, it is deflected upward by the wedge projection 24 at the discharge opening and impinges against the under side of the shield, 23, from which it is spread out laterally and distributed over a wide range of grate area throughout the length of the fire box. 95

Having now described our invention, what we claim as new, and desire to secure by Letters Patent, is:

In a mechanical stoker, the combination

with a furnace wall having an opening, of a fuel distributed comprising an elbow outside the wall and provided with fuel and fluid pressure connections, a flat flaring distributing hood within the furnace and having an integral tubular shank extending through and closely fitting said opening and detachably connected to said elbow, said hood having diverging depending flanges, 10 and an upwardly inclined deflector at the

bottom of the discharge end of said tubular shank.

In testimony whereof we have hereunto set our hands.

CLEMENT F. STREET.
NATHAN M. LOWER.
